UNITED STATES PATENT OFFICE

JAMES HENRY HELY, OF FRESNO, CALIFORNIA; L. ST. JOHN HELY ADMINISTRATOR OF SAID JAMES HENRY HELY, DECEASED.

DEVICE FOR GENERATING GAS FOR USE IN INTERNAL-COMBUSTION ENGINES.

1,164,515.

Specification of Letters Patent. Patented Dec. 14, 1915.

Application filed May 25, 1914. Serial No. 840,892.

To all whom it may concern:

Be it known that I, JAMES HENRY HELY, a citizen of the United States, and a resident of the city of Fresno, county of Fresno, and State of California, have invented a new and useful Device for Generating Gas for Use in Internal-Combustion Engines, of which the following is a specification.

My invention relates to a device for generating gas from crude oil for use in internal combustion engines, and its object is to readily extract all the combustible gases from such crude oil, to keep such gases in a gaseous state until it reaches the compression chamber and for other purposes which will hereinafter more fully appear.

In the drawing accompanying my specification Figure 1 represents a sectional view of the gas generator complete. Fig. 2 is a sectional view along line *a* on Fig. 1.

In said drawing 2 is an outer casing.

21 is a cap adapted to close the upper end of such outer casing and 22 is a cap adapted to close the lower end of the outer casing and to be easily removable.

Outer casing 2 has an opening 23 on one side in the form of a tube running at an acute angle from the wall of the outer casing and pointing upward. This tube can be constructed integral with outer casing 2.

24 is an air chamber encircling outer chamber 2.

25 are openings through the wall of air chamber 24 to admit air to the inside of such chamber.

31 is an exhaust port.

3 is a lead connecting exhaust port 31 with opening 23.

32 is an air chamber encircling lead 3, and 33 are openings into air chamber 32, the purpose of which will hereinafter more readily appear.

4 is an inner tube adapted to fit into outer casing 2 with an air space 41 between the inner tube and outer casing. Tube 4 is preferably constructed of metal.

43 is a cap which fits neatly over the upper end of tube 4, and 42 is a cap which fits over the lower end. Cap 42 has a depending hollow projection 46 which is fitted to rotate in a bearing 26 in cap 22.

At the end of hollow projection 46 I have placed a valve 5, the object of which is to permit the discharge of the refuse which is

extracted from the gas producing elements 55 injected into the inner tube 2. Valve 5 consists of a T member, the upper end of which rests in a seat 52 at the lower end of hollow projection 46, which end is open. This valve is held in a normally closed position by 60 means of a spring 53. 54 is an opening through the wall of cap 22, and is constructed to allow the refuse to pass through when valve 5 is pressed down sufficiently to permit opening 54 to communicate with hollow 65 extension 46. Cap 43 has a hollow extension 48 which is adapted to rotate in a bearing 27. Hollow extensions 46 and 48 are on line when the generator is assembled, the object being to permit the inner tube to be rotated 70 within the outer casing.

6 is a wheel attached to extension 48 being adapted to transmit power for rotating caps 43 and 42 and the inner tube 4. In my construction I have inner tube 4 fitted neatly 75 into caps 42 and 43, so the generator is approximately gas proof. It is well known that gas generators which use crude oil readily become incrusted with the refuse from the oil and the construction herein 80 above referred to permits the inner tube 4 to be readily removed by loosening bolts 28 and removing caps 22 and 42, when a clean inner tube can be readily inserted.

11 is a member which fits at a running fit 85 the opening in projection 48. Member 11 is hollow and closed at the top with cap 9 which can be constructed integral with member 11.

12 is the conductor from member 11 to the 90 compression chamber of the engine and is covered with heat non-conducting material.

8 is a lead which carries the crude oil to the interior of the inner tube and the flow of the oil is regulated by means of a valve 95 81 or other device in common use for such purposes. I have adapted lead 8 to deposit the oil at the upper end of the inner tube, where the heat from the exhaust port 31 first strikes inner tube 4, and therefore at its hot- 100 test portion. In installing this gas generator I have inclined it at an angle of approximately 45 degrees. It will be observed that as the crude oil is deposited on the interior of the inner tube, with the inner tube rotating 105 and leaning at an angle from the perpendicular the oil will slowly spread over the interior of the inner tube and flow toward the

bottom of such tube, and as the tube is kept warm by the hot air from the exhaust ports the gases in the crude oil are released.

49 is an opening in the wall of outer casing 2 and is adapted to carry off the burnt gases which pass into the space 41 from the exhaust port 31. This opening (49) should be above cap 22 so cap 22 can be more easily removed. It is further observed that the residue of the crude oil after the release of gas therefrom carbonizes more readily on the inner tube than crude oil in its natural state. To meet this I have first applied the heat from the exhaust port of such inner tube and deflected it downward.

10 is a bracket attached to outer casing 4, adapted to hold member 11.

To supply hot air to the interior of the inner tube I have run a pipe from air chamber 32 to the interior of inner tube 4. 7 is a lead for the purpose of injecting water into the inner tube. By means of a valve 71 or other devices in common use the amount of water and air admitted to the inner tube 25 can be regulated so the mixture will produce gas of high efficiency. Leads 7, 8, and pipe 34 are inserted into inner tube 4 through member 11.

It is further to be noted that low grade 30 gas sometimes liquefies in passing from the gas generator to the intake on the cylinder. To overcome this objection I have connected pipe 13 with air chamber 24, and to intake pipe 12 for the purpose of drawing 35 the hot air surrounding outer casing 2 into the mixture. The amount of air thus admitted can be regulated by a valve 17 or by any means now in use for such purposes.

What I claim as my invention for which I 40 desire Letters Patent is:

i. In a crude oil gasifier for an internal combustion engine, a casing, an inclined tube within the casing and separated therefrom to form a heating space, means for supplying 45 heat to such heating space, closures at each end of such tube, means for rotating the tube in said casing, means for supplying fuel at the upper end of such inclined tube, means for conducting gas from such inclined tube, and means for discharging fuel refuse from such inclined tube consisting of an outlet in the lower part of such tube, a valve constructed to normally close

such outlet, and when weight is placed thereon from within such tube, to open such outlet, all substantially as described.

2. In a gasifier for an internal combustion engine, for using crude oil as fuel, an inclined outer casing, an inclined rotary tube therein separated from the outer casing to provide a heating chamber between such outer casing and such tube, a pipe attached to such outer casing at an oblique angle thereto pointing downward, communicating with the inside of such outer casing, and constructed to conduct heating fluid to the heating chamber between such outer casing and such inner chamber, and to deflect such heat downward, an outlet for such heating fluid through such outer 70 casing near the lower end thereof and through the portion of the wall opposite to where such heating fluid is conducted into such heating chamber, outside means for rotating such inner chamber, means for depositing such crude oil within such inner chamber upon the inside wall and near the top thereof, and means for conducting gas from such chamber.

3. In a crude oil gasifier for an internal 80 combustion engine, a heating casing having independent closures at each end, an inclined tube within such heating casing having independent closures at each end, the closure of the upper end of such tube being 85 journaled within the closure of the upper end of such heating casing, and the closure of the lower end of the tube being journaled within the closure of lower end of such casing, such tube being constructed to 90 be easily removable from such tube closures, and to fit snugly within such tube closures when the casing closures are attached to the casing and to be separated from such heating casing, means for fastening such independent casing closures to such casing, means for supplying exhaust gases to the inside of the heating casing, means for supplying crude oil and gas producing elements to the interior of such tube, means for conducting gas from such tube, and means for discharging the fuel refuse from such tube.

JAMES HENRY HELY.
